UNITED STATES PATENT OFFICE.

WALLACE E. MOORE, OF MERIDEN, CONNECTICUT, ASSIGNOR TO THE AMERICAN HARDWARE CORPORATION, OF NEW BRITAIN, CONNECTICUT, A CORPORATION OF CONNECTICUT.

DOOR CLOSER.

Application filed June 17, 1927. Serial No. 199,514.

My invention relates to improvements in door closers and has for its object to provide a new and improved hold-back door closer which is easy to manufacture and assemble, 5 positive in its action, and more durable than those heretofore used. It also has for its object to provide a hold-back door closer having a detent comprising a ball which cooperates with a stop to hold the door in 10 retracted position and is freely rotatable in any direction when in non-holding position, so as to present a larger number of changing surfaces to the stop and do away with objectionable features in constructions now 15 used.

Heretofore hold-back door closers have been made having a detent or pawl carried by the door closing lever and held in yielding engagement with a stop by means of a 20 spring carried by the arm. These pawls have consisted either of a member having a non-rotating face engaging the stop or a member having a stop engaging roller mounted upon a pin. Where the engaging 25 face did not rotate, objectionable friction was present and the same portion of the member repeatedly engaged the stop. Where a roller was used, the same portion of the roller repeatedly engaged the stop be- 30 cause there is no rotation after the stop is disengaged and the one rotation is about a fixed axis. The roller is subject to wear at a given point, resulting in a depression caus- 35 ing a harder blow upon the stop, and, fur- thermore, the pin upon which the roller is 40 mounted wears away and finally breaks so as to permit the roller to be displaced. The use of a ball has been suggested but such 45 ball was restrained from movement by its housing after leaving the stop so that it was subjected to repeated blows at the same point, resulting in wear, and, furthermore, so much of the ball was contained within the housing as to not produce the proper holding action.

With the improved construction a loose ball is used which, when out of engagement with the stop, is supported by the stop carrying member and rolled along thereon so 50 that, practically speaking, a new portion of

the ball is presented to the stop upon every operation of the check, and the ball shows no appreciable signs of wear during the life of the check. Moreover, the recess forming the housing for the ball is not contracted at 55 its lower end and thus is easier to form.

The following is a description of an embodiment of my invention, reference being had to the accompanying drawings, in which:

Fig. 1 is a plan view of a door closer embodying my invention;

Fig. 2 shows a portion of the same partly in side elevation and partly in section on the line 2—2, Fig. 1 with the lever shifted to hold back position; and

Fig. 3 is a detail section on the line 3—3, Fig. 1.

Referring more particularly to the drawings, 2 is a door hinged at 4 and 6 is a door casing, one portion of the closer being 70 mounted upon the door and the other portion being connected to the casing in the ordinary manner. 8 is a member of the closer secured to the door, the same comprising a cover 10 having thereon an adjustable 75 ring 12 carrying a stop 14 having a pocket 16. 18 is the ordinary spring driven shaft of the closer, on which is mounted a lever 20 connected to the link 22. The lever carries a double ended detent 24, one end of 80 which engages teeth upon a ratchet member 26 connected to the door closing spring, the features thus far described being of ordinary construction heretofore used.

The lever arm 20 is provided with a round 85 vertical recess 28 having within it a shoulder or abutment 30 and containing a compression spring 32, which is held in place by a screw plug 34 having a screw-driver slot and by which the compression of the spring 90 can be adjusted. Below the spring is a plunger 36 having a flange 38 which engages the shoulder 30, and below the abutment is a hardened steel ball 40, whose diameter is slightly less than the diameter of 95 the mouth of the recess which is opposed to the member 8. This ball 40 is thus free to pass in and out of the mouth of the recess except as its movement is limited by the member 8, and is held within that recess 100.

solely by said member 8 and the stop 14. When the ball is in engagement with the stop 14, substantially one-half of the ball is outside the recess, so that in spite of the 5 clearance between the stop and the lever arm a large portion of the ball is within the pocket 16, thus resulting in a strong holding relation when the ball is within the pocket 16. The distance between the lower 10 end of the plunger 36 and the bottom of the pocket, when the flange 38 is in engagement with the shoulder 30, is preferably equal to the diameter of the ball, although it may be slightly less or greater than that 15 diameter. The mouth of the recess 28 constitutes a housing for the ball and is opposed to the member 8.

When the ball is not in the pocket 16, the shoulder 30 prevents the spring and also the 20 plunger 36 from acting upon the ball so that at that time the ball is free to revolve without substantial friction in any direction. The presence of the plunger 36 prevents the ball from directly engaging the spring at 25 any time so that the ball does not tend to spread the convolutions of the spring and cause it to bind within the recess 28.

In manufacturing the device, the lever 20, together with the spring 32, plunger 36, and 30 adjusting plug 34, are assembled, and as the lever is put upon the shaft 18 the ball is inserted in place.

The pawl 24 preferably has a ring shaped portion surrounding the lower end of the 35 wall of the recess 28, which is upset so as to hold it in position, the ball 40 being concentric therewith.

When the closer is in action, the hardened 40 steel ball moves around with the lever 20, and when resting upon the flat surface of the member 8 is supported thereby out of contact with the plunger, rolling freely thereon in any direction. When the lever 20 is moved so that the ball engages the stop 45 it is in passing the stop lifted up into its housing until it engages the plunger 36, compressing the spring 32 until it reaches the pocket 16, whereupon it is forced downward by the spring and plunger into said 50 pocket, engaging the same and holding the lever 20 in retracted position, being then substantially half within its housing and half outside its housing, as shown in Fig. 2. When the ball 40 rests upon the member 8 55 it is sufficiently within its housing so that when it engages the inclined surface on the stop 14 it is moved easily into the housing until it engages the plunger 36, after which it acts to compress the spring 32.

60 The ball 40 and the closed end of the recess constitute abutments for the spring 32 when the ball is passing the stop 14. One of said abutments is spaced away from said spring when the ball is not in engagement with said stop so that the spring does not

then exert upon the ball pressure due to the expanding action of the spring.

The recess 28 is a round, vertical recess and can therefore be made by a simple drilling operation at right angles to the axis of 70 the lever 20. 42 is the door closing spring acting on lever 20 in usual manner.

The stop 14 being carried by the adjustable ring 12 can be moved angularly and fixed in any desired position. The door can 75 be opened beyond the holding position of the lever if desired.

As will be evident to those skilled in the art, my invention permits of various modifications without departing from the spirit 80 thereof or the scope of the appended claims.

What I claim is:

1. In a door closer having a member carrying a stop fixed thereto and a spring actuated door closing lever carried by said member and movable relatively to said stop, the improvement which consists in a recess in said lever having a mouth opposed to said member, a ball within said mouth of smaller diameter than said mouth so as to be free to pass therethrough, said ball being at all times in rolling contact with said member and held within said recess by said member, and a compression spring within said recess compressed by said ball when passing said stop so that pressure due to the expanding action of said spring is then exerted upon said ball, but uncompressed by said ball when out of engagement with said stop so that said ball is then free from such pressure, the ball and the end of the recess constituting abutments for said spring when the ball is passing said stop, one of said abutments being spaced away from said spring when the ball is not in engagement with said stop. 100

2. In a door closer having a member carrying a stop fixed thereto and a spring actuated door closing lever carried by said member and movable relatively to said stop, the improvement which consists in a recess in said lever having a mouth opposed to said member, a ball within said mouth of smaller diameter than said mouth so as to be free to pass therethrough, said ball being at all times held within said recess by said member, a compression spring within said recess compressed by said ball when passing said stop, and a shoulder within said recess 110 restraining said compression spring from acting on said ball when said ball is out of engagement with said stop. 115

3. In a door closer having a member carrying a stop fixed thereto and a spring actuated door closing lever carried by said member and movable relatively to said stop, the improvement which consists in a recess in said lever having a mouth opposed to said member, a ball within said mouth of smaller diameter than said mouth so as to be free 120 125 130

to pass therethrough, said ball being at all times held within said recess by said member, a compression spring within said recess compressed by said ball when passing said stop, a plunger between said spring and ball, and a shoulder within said recess restraining said spring and plunger from acting on said

ball when said ball is out of engagement with said stop.

In testimony whereof, I have signed my ¹⁰ name to this specification this 13th day of June, 1927.

WALLACE F. MOORE.
